UNITED STATES PATENT OFFICE.

CHARLES L. PARTRIDGE, OF OMAHA, NEBRASKA.

PRECISION SAW.

1,283,551.

Specification of Letters Patent.

Patented Nov. 5, 1918.

Application filed May 8, 1917. Serial No. 167,237.

To all whom it may concern:

Be it known that I, CHARLES L. PARTRIDGE, a citizen of the United States, residing at Omaha, in the county of Douglas and 5 State of Nebraska, have invented certain new and useful Improvements in Precision-Saws; and I do hereby declare the following to be a full, clear, and exact description of the invention, such as will enable others 10 skilled in the art to which it appertains to make and use the same.

This invention relates to improvements in saws of the type ordinarily used for cutting slugs of metal for printing offices, although 15 the invention is not necessarily limited to such use.

The invention has for its object to provide an improved machine including a traveling rotary saw and an adjustable support 20 for the carriage of the saw to permit the latter to be fed into the work.

Another object is the provision of a sawing machine including a mitering mill supported by and adjustable with the vertically 25 movable table and operatively connected with the driving means for the saw.

With these and other objects in view, the invention consists in the novel construction, combination and arrangement of parts as 30 will be hereinafter specifically described, claimed and illustrated in the accompanying drawings, in which:

Figure 1 represents a front elevation, partly in section, of the improved saw,

Fig. 2 represents an end elevation of the sawing machine,

Fig. 3 represents an elevation of the opposite end of the saw,

Fig. 4 represents a top plan view of the machine.

Fig. 5 represents a detail sectional view through the table top on the line 5—5 of Fig. 4,

Fig. 6 represents a detail sectional view 45 on the line 6—6 of Fig. 1,

Fig. 7 represents a bottom plan view of the mitering cutter carriage removed,

Fig. 8 represents a fragmentary side elevation of one of the legs of the machine,

Fig. 9 represents a detail view of the gear shifting device.

Referring to the drawings in detail, wherein similar reference numerals designate corresponding parts throughout the 55 several views, the numeral 10 indicates a supporting base carrying upstanding legs

11 supporting a bed plate 12. A sub-base 13 is adjustably supported upon the bolts 14 fastened to the base plate 10 and supports an electric motor 15 to provide power to 60 operate the machine. A track 16 is secured by bracket arms 17 to one leg 11 of the supporting frame structure and slidably supports a horizontally movable carriage 18, which is provided at its upper terminal with 65 horizontal bearings 19 rotatably supporting the saw arbor 20. The saw 21 is secured to the inner terminal of the arbor 20 and is movable back and forth transversely of the bed plate 12.

An inclined board 5^a is arranged underneath the saw 21 for guiding the sawdust onto a second board 6^a, which is so arranged as to deflect the dust away from the sawing machine.

A belt, or other power transmitting device 22, is extended over the pulley 23 of the motor shaft 24 and extends upwardly over a pulley secured to the saw arbor 20 for driving the latter during operation of 80 the machine, and an idler pulley 25^a is provided to take up the slack in the belt 22 incident to the movement of the carriage across the bed plate 12.

A table 25 is arranged on the right side of 85 the saw 21 and is pivotally supported on a hinge rod 26, which extends through apertured ears 27 depending from the table 25 and apertured ears 28 formed on the bed plate 12.

A vertically adjustable table 29 is arranged on the left side of the saw 21, and is supported upon a standard or post 30, which extends down through the bed plate 12 and is supported in guides 31. A hook 32 is connected with the post 30 and the hook is engaged by a link 33, which is connected with a crank 34 on a shaft 35, which latter is provided at its forward terminal with a handle 36, whereby the shaft may be conveniently 90 rocked to oscillate the crank 34 and elevate or lower the post 30 and table 29, as desired. By proper vertical adjustment of the table 29, the work may be brought into proper relation to the saw 21 to insure the most efficient cutting action of the latter.

A head gage 37 is formed on the front portion of the table 29 and is preferably provided with pica or other standard measurements designed to assist in accurately adjusting the side gage 38, which is slidably mounted upon the head gage 37. The work

is held or clamped in engagement with the head gage 37 by a clamping member 39, which is operable by a screw carrying a knob 40 for convenience in adjusting the 5 clamping member. The specific construction of the adjusting means for the clamping member 39 is described and claimed in another application for patent.

An auxiliary head gage 41 is secured upon 10 the table top 29 rearwardly of the main gage 37 and slidably supports an auxiliary side gage 42. At the inner terminal of the auxiliary gage 41 a slot 43 is formed in the table top 29 and the walls of the slot are 15 enlarged and grooved to provide guides for a carriage 44, which is slidably mounted therein.

The carriage 44 supports a vertically disposed shaft 45, carrying a pulley 46 at its 20 lower end and a rotary cutting element 47 at its upper end, having inclined teeth or cutting members designed to miter or bevel the edges of a metal slug. The cutting element 47 is secured in position upon the 25 shaft by a thumb screw 48 and the carriage is moved longitudinally in the groove 43 by an adjusting or actuating member 49, including a vertically disposed shaft journaled in the table 29 carrying a handle 51 at its 30 upper terminal, and an angularly disposed crank arm 52 at its lower terminal. A pin 53 is formed integral with the outer terminal of the arm 52 and is engaged in a slot 54 formed in the carriage 44, whereby the 35 latter is adjusted longitudinally in the slot 43 during swinging movement of the handle 51 to move the cutting element 47 across the work engaged with the head gage 41.

Rotary movement is imparted to the rotary cutting element 47 from the motor shaft 24 by a belt 55, or other power transmitting device, which is extended over the pulley 46, idler pulleys 56 arranged under the table 29 and also over a pulley 57 secured 40 upon a vertically disposed shaft 58. The shaft 58 is swivelly mounted at its upper terminal in a bearing 59 secured under the table top 29 and is supported at its lower terminal in a bearing member 60, pivotally 45 mounted in inwardly directed pins 61 carried by curved supporting arms 62, which latter are pivotally mounted at their lower terminals on a bolt 63 secured to an outwardly directed lug 64 formed upon a vertically 50 adjustable plate 65. A friction pulley 66 is slidably mounted upon the shaft 58 above the bearing member 60 and is engaged with a friction disk 67 secured upon the adjacent terminal of the motor shaft 24, where- 55 by when the disks are moved into frictional engagement rotary movement is transmitted from the shaft 24 to the shaft 58. A pulley 58^a is mounted upon the shaft 58 a short distance below the bearing 59. 60 The plate 65 is secured in adjusted position 65

by bolts 68 positioned through slots 69 in the plate and threaded in the adjacent supporting leg 11 of the sawing machine.

By swinging the pivoted arms upon their pivotal axis 63, the friction disk 66 is moved 70 into and out of engagement with the friction disk 67 at the will of the operator, and the adjustment of the pivoted arms is effected by an eccentric 70 rotatably mounted in the leg 11 under the bed plate 12 and 75 connected with an eccentric strap 71, carried by a rod 72^a which latter is connected at its lower terminal with a laterally projecting ear 73 formed on the arms 62. By shifting the eccentric 70 from one position to another 80 the arms 62 are moved inwardly and outwardly with relation to the friction disk 67. A handle 72 is connected with the shaft carrying the eccentric 70 for convenience in adjusting the latter and is movable against 85 pins 73^a formed integral with the leg 11 and constituting stops for limiting the swinging movement of the handle 72.

What I claim is:

1. In a sawing machine, a bed plate, a vertically adjustable table, a post carried by the table, a pivoted handle and a link and arm in connection between the post and the handle for adjusting the table.

2. In a sawing machine, a bed plate, a vertically adjustable table, a post carried by the table and extending through the bed plate, a crank shaft, a handle carried by the crank shaft, and means connecting the crank pin of the shaft with the post to adjust the latter vertically.

3. In a sawing machine, a supporting frame, a vertically adjustable table arranged above the supporting frame, a rotary cutting element supported upon the table, a shaft 105 swivelly mounted underneath the table, means connecting the shaft with the rotary cutting element, a drive shaft rotatably mounted in the frame, driving connections between the first and second-mentioned 110 shafts, and means for swinging the first-mentioned shaft out of driving engagement with the second-mentioned shaft.

4. In a sawing machine, a supporting frame, a table arranged over the frame, 115 means for adjusting the table vertically, a circular saw arranged laterally of the table, a rotary cutting element supported by the table and having its axis arranged at right-angles to the axis of the saw, and means for 120 driving the cutting element.

5. In a sawing machine, a table, a supporting frame therefor, a rotary cutting element mounted upon the table, a shaft pivotally and rotatably supported by the table, means 125 connecting the shaft with the cutting element, a drive shaft, a friction disk carried by the drive shaft, a friction disk carried by the lower terminal of the first-mentioned shaft, and means for swinging the lower 130

terminal of the first-mentioned shaft inwardly to engage its friction disk with the friction disk of the drive shaft.

6. In a sawing machine, a supporting 5 table, a rotary saw arranged laterally of said table, a rotary cutting element supported by said table and having its axis arranged at right angles to the axis of the saw, a drive shaft, means for adjusting said table vertically and flexible guiding connections between the drive shaft and the rotary cutting element permitting vertical movement of the table.

7. In a sawing machine, a supporting 15 frame, a table mounted thereon, a rotary saw arranged laterally of said table, and a rotary cutting element mounted upon the table and having its axis arranged at right angles to the axis of the saw.

20 8. In a sawing machine, a supporting frame, a table mounted thereon, a rotary saw arranged laterally of said table, a rotary cutting element, means movably supporting the rotary cutting element upon the table 25 and permitting movement thereof in the direction of the cut of the rotary saw.

9. In a sawing machine, a supporting 30 frame, a table mounted thereon, a rotary saw arranged laterally of said table, a rotary cutting element, means movably supporting the rotary cutting element upon the table and permitting movement thereof in the direction of the cut of the rotary saw, said cutting element having its cutting surface 35 beveled to miter the edges of material cut by said saw.

10. In a sawing machine, a bed plate, a vertically adjustable table, a post carried by the table and extending through the bed plate, a crank shaft, a handle carried by said 40 crank shaft, means connecting the crank pin of the shaft with said post to adjust the post and table vertically, a rotary saw arranged laterally of said table, a rotary cutting element, means movably supporting the rotary 45 cutting element upon the table and permitting movement of the cutting element in the direction of the cut of the rotary saw.

11. In a sawing machine, a supporting 50 frame, a vertically adjustable table arranged above the supporting frame, a post carried by the table, a pivoted handle, a link and arm connection between the post and the handle for adjusting the table, a rotary cutting element supported upon the table, a 55 shaft swivelly mounted beneath the table, means connecting the shaft with the rotary cutting element, a drive shaft rotatably mounted in the frame, driving connections between the first and second mentioned 60 shafts, means for swinging the first mentioned shaft out of driving engagement with the second mentioned shaft, a rotary saw arranged laterally of said table, said cutting element having its cutting surface beveled to 65 miter the edges of material cut by said saw.

In testimony whereof I affix my signature in presence of two witnesses.

CHARLES L. PARTRIDGE.
